UNLOADER FOR COMPRESSORS AND OTHER DEVICES.

1,404,175.

Specification of Letters Patent. Patented Jan. 17, 1922.

Application filed December 19, 1914. Serial No. 878,187.

To all whom it may concern:

Be it known that we, FRED D. HOLDSWORTH and CHARLES W. WYMAN, citizens of the United States, and residents of Claremont, N. H., have invented an Improvement in Unloaders for Compressors and other Devices, of which the following description, in connection with the accompanying drawings, is a specification, like characters on the drawings representing like parts.

This invention relates to elastic fluid compressors, and more particularly to compressors of the multi-stage type.

15 In the operation of air compressors which are driven by an external source of power which runs at a constant speed, such as electric motors, gas or gasoline engines, in order to maintain a constant air pressure, it is necessary to interrupt the flow of air through the machine when the pressure in the receiver reaches the desired point, and re-establish the flow as soon as the pressure in the receiver has fallen a few pounds.

25 This is usually accomplished by placing a balanced valve, commonly called an unloading valve, on the main inlet supply to the compressor and attaching to this valve a suitable piston, which moves the valve to its 30 open or closed position under control of a small regulator which is piped to the main air receiver. When this unloading valve is closed as a result of the rise in the receiver pressure, the compressor rapidly forms a 35 more or less complete vacuum in all of its internal air passages. Owing to the construction of this form of unloading valve,

it is difficult to make it absolutely air-tight when it is closed, and it is difficult to 40 prevent other air leaks about the machine, so that a small quantity of air flows through the machine, which air has to be compressed and delivered to the main receiver. Instead of compressing this air from ordinary 45 atmospheric pressure, however, it may be compressed from only one or two pounds absolute pressure up to receiver pressure. This greatly increases the ratio of compression, and, as the heat generated in 50 compression is directly dependent upon the

number of times the air is compressed, it will readily be seen that when the air reaches its final pressure in the air-cylinder, it will be heated very much in excess of the temperature obtained in compression under 55 normal running conditions with the inlet-opening wide open. This high temperature is detrimental to the oil used for lubrication, and is a source of danger, inasmuch as the extreme heat may ignite the oil, or if 60 the oil is diffused through the air in proper proportions, an explosion may result. This is especially true of multi-stage compressors where the pressure is carried to several hundred pounds per square inch. This invention is more particularly concerned with the provision of an auxiliary unloading valve which may be employed in connection with the second or high-pressure cylinder of a two-stage compressor, or with the sec- 65 ond and third cylinders of a three-stage compressor, or with the succeeding cylinders of a compressor of any desired number of stages. By this auxiliary valve there is a saving in power when running unloaded, 70 as the small quantity of air flowing through the cylinder due to leakage is compressed and discharged at practically atmospheric pressure instead of receiver pressure.

Our invention will be best understood by 80 reference to the following description, when taken in connection with the accompanying illustration of one specific embodiment thereof, while its scope will be more particularly pointed out in the appended 85 claims.

In the drawings:

Fig. 1 is a plan of a compressor embodying our invention;

Fig. 2 on an enlarged scale is a vertical 90 section through an auxiliary unloading valve embodying the invention;

Fig. 3 is a detail of a modification to be referred to;

Fig. 4 is a longitudinal vertical section of 95 one end of a high pressure cylinder which in the present embodiment is of the double acting type, both ends being similar in construction;

Fig. 5 is an end elevation of the low 100

pressure cylinder showing the unloading valve on the main inlet supply to the compressor; and

5 Fig. 6 is a vertical section through a portion of an auxiliary unloading valve showing a modification of the construction disclosed in Fig. 2.

10 Referring to the drawings and to the embodiment of our invention which we have there disclosed, for illustrative purposes, we have there shown a multi-stage compressor, herein having two cylinders (Fig. 1), a low-pressure cylinder 5 and a high pressure cylinder 6, the former drawing its supply 15 from an inlet pipe 7 (Fig. 5). The compressed air is delivered by said low pressure cylinder to an intermediate receiver 11, which as is usual cools the air before it passes to the high-pressure cylinder. This 20 receiver, which is commonly called an inter-cooler, delivers the air into an inlet chamber 12 (Fig. 4) of the high-pressure cylinder 6, whence it passes to an outlet chamber 13, as will appear hereinafter. This outlet chamber in practice is connected to a main receiver which we have not shown herein as it is unnecessary to the illustration of our present invention.

25 The main inlet 7 may be controlled as is usual by means of a main unloading valve 14 (Fig. 5) of the balanced type. This valve is usually controlled by a suitable piston which moves the valve to its open or closed position under control of a small 30 regulator which is piped to the main air receiver, these parts being of usual and well-known construction, and a further description of them being unnecessary to an understanding of our present invention.

35 40 Referring now to Fig. 4, there is shown therein one end of the high pressure cylinder 6, herein of the double acting type, the other end being precisely similar in construction. This cylinder is provided with a head 15 in which is located an inlet valve 16 which may be of any usual or desired construction, the same being herein of the oscillating type, being given an oscillating motion at the proper intervals in the operation 45 50 of the machine by a suitable mechanism (not shown).

55 The cylinder is also provided as usual with a discharge valve 17 which may be of any usual construction, herein being provided with a spring 18 tending to seat the same and operating as usual to open and permit the air compressed in the cylinder to flow into the outlet chamber 13 and thence to the usual main air receiver.

60 65 Within the cylinder 6 is a usual piston 19 which, when moved toward the right (Fig. 4) draws the air through the inlet chamber 12 and its connections with the low pressure cylinder 5, and upon the closing of the inlet valve 16 the piston moves toward the left.

thereby compressing the air in the usual manner; and when the pressure in the cylinder is equal to or slightly greater than the pressure in the discharge chamber 13 the discharge valve 17 will lift from its seat and 70 allow the air to be forced out of the cylinder.

75 Next will be described the auxiliary unloading valve shown herein as applied to the high pressure cylinder. Since the latter is double acting an auxiliary valve is connected to each end of the cylinder, but as the valves at both ends are similar a description of one will suffice for both.

80 Referring more particularly to Fig. 2, this valve comprises a cylinder 20 mounted on a base 21 and communicating with a chamber 21^a therein, said base being connected by a pipe 22 with one end of the cylinder and by a pipe 23 with the outside atmosphere. This chamber has a wall 24 85 formed with a reverse bend presenting registering openings one of which is somewhat larger than the other and constituting seats for receiving a differential valve 25 having a stem 27 guided by a bore in a thickened portion of the lower wall of said base 21.

90 To normally hold said differential valve on its seat there is provided in the cylinder 20 referred to a piston 28 urged downward by a heavy spring 29 confined between said 95 piston and the top of said cylinder. To further contribute to the control of the differential valve, as more fully hereinafter described, it is pressed down on its seat by a light helical spring 30 encircling a stud 31 100 projecting from a recessed hub 33 of said piston, said spring being confined between the end of the recess in said hub and the differential valve. To further contribute to the guidance of the differential valve, its 105 stem is extended upward into a bore 34 in said stud. A passage 35 completes the communication between the cylinder 20 and the pipe 22 and is provided with a spring 110 pressed check valve 36.

115 In operation, after the unloading valve 14 is closed by the rise in the receiver pressure, the compressor rapidly forms a more or less complete vacuum in the cylinder 6. For example, when the compressor piston 19 115 moves toward the right (Fig. 4) it creates more or less of a vacuum in the cylinder on the left of the piston and also in the pipe 22, the chamber 21^a and the passage 35. This opens the check valve 36 and creates 120 more or less of a vacuum in the cylinder 20. The lower face of the piston 28 is continuously exposed to the outside atmosphere through the pipe 23. Consequently when a sufficient vacuum has been created in the 125 cylinder 20, the piston 28 is lifted against the resistance of the heavy spring 29 and the contact between said piston and the differential valve 25 is broken. As a result 130 said valve becomes free to lift against the

pressure of the light spring 30 and the pressure of the atmosphere.

When the compressor piston 19 returns to the left of the cylinder, the small quantity 5 of air in the cylinder at the left of the piston under reduced pressure or partial vacuum will be compressed and, when the pressure thus formed slightly exceeds the pressure of the atmosphere, the differential valve 10 will rise from its seats and allow this air to escape to the atmosphere through the pipe 23.

After the receiver pressure has dropped slightly the unloader valve 14 automatically 15 opens in the usual manner and the work of compression is resumed. As the pressure builds up in the inter-cooler and high pressure cylinder, the vacuum condition there is destroyed and leakage past the auxiliary 20 valve piston 28 quickly destroys the vacuum which existed above it. The piston is then forced downward by the heavy spring 29 to and into engagement with the differential valve, thereby holding it firmly to its seat. 25 This spring is made sufficiently strong to hold the differential valve seated when the maximum working pressure of the compressor is obtained, so that none of the air compressed in the normal operation of the compressor is wasted.

If desired, a minute vent hole 37 may be made in the cylinder 20 and be provided with a needle valve 39 for regulating the opening therein. Thus the leakage of air 35 into the cylinder 20 may be regulated and controlled as required.

A single disk valve might be employed in place of the differential valve shown herein, but if so a stronger spring would be required 40 to hold the valve to its seat and the piston and spring would not be as quickly responsive to the vacuum condition as those shown herein. It is therefore preferable to employ the differential valve.

45 As stated, auxiliary devices are provided for both ends of the compressor cylinder. To insure simultaneous action in them it is desirable to connect the cylinders 20 thereof by a small pipe 41 (Fig. 1). When thus 50 connected the vacuum conditions in both of the chambers 20 above their pistons will be equalized and said pistons will lift simultaneously out of contact with their differential valves and the air on the opposite 55 sides of the compressor piston will be free to escape readily past the differential valves to the atmosphere.

There are very important advantages in these auxiliary unloader valves, since after 60 the pressure in the receiver has reached a predetermined amount, they automatically release the air from the compressor and permit the latter to continue to operate without performing any substantial work of compression. This lightens the burden on the

driving mechanism for the compressor and prevents the objectionable high heating of the apparatus. It will be observed that these auxiliary unloader valves are operated directly by the pressure condition within the 70 compressor cylinder and independently of the pressure in the inter-cooler. By the direct connection of the auxiliary unloader valves to the cylinder it will also be noted that it is not only possible to utilize a higher 75 vacuum and thus obtain greater certainty in operation of the valves, but it is also possible to eliminate entirely any connection between the valves and the intercooler. Attention is also directed to the fact that it is 80 thus possible for the valves, if desired, to be applied to the usual indicator openings found in a standard compressor cylinder without any other change in the machine, the valve mechanism itself constituting a 85 unitary device readily attachable to a standard machine. Also these auxiliary unloader valves do not operate simultaneously with the actuation of the main unloader valve, but subsequently thereto since the compressor piston must reciprocate to create a 90 vacuum condition in the compressor cylinder sufficient to lift the piston 28 against the resistance of the heavy spring back of it before the differential valve can open. Due to this 95 retarded action, the partially compressed air in the intercooler is compressed to the receiver pressure instead of being discharged to the atmosphere. A further very important result obtained is that due to the 100 fact that little air is left in the intercooler at the time that the unloading valve opens, the size of this valve may be very much smaller and still handle without undue resistance, the air rejected from the compressor during 105 unloading operation.

In Fig. 3 is shown a modification in which auxiliary unloading valves are provided substantially similar to the one described, but instead of being connected merely by a small 110 pipe 41 (as shown in Fig. 1), they are connected by a pipe 43 having an intermediate branch pipe 45 connecting the same with the compressor cylinder near or at the middle of its length and provided with a check valve 115 47 therein. This check valve may be similar to the check valve 36 referred to and therefore it is not necessary to show the same in detail herein. This arrangement would render unnecessary the passage 35 and the location of the check valve 36 therein.

In Fig. 2 the differential valve is shown as having guiding stems projecting in opposite directions therefrom, one being guided in a bore in the base of the casing and the other being guided in the hub of the spring pressed piston. In Fig. 6 is shown a modified construction comprising a differential valve 49 having a bore receiving a guide stem or pin 51 made fast in a bore in the casing register- 125 130

ing with the openings for the differential valve. When the spring pressed piston is lifted from the valve the latter will be free to slide on its stem when the pressure in the chamber exceeds the atmospheric pressure effect on the outer faces of said differential valve.

It will be observed that the lower hole for the differential valve and the hole for the guiding pin are of the same size and may be made in one boring operation with the same tool, thereby insuring the accurate alignment of the guide pin with the valve and the accurate fitting of said valve on its seats.

15 The differential valve with the bore therethrough as described finds a strong and substantial guidance from the pin projecting upward therein. Since both ends of the differential valve are exposed to the outside atmospheric pressure, the bore in the valve may extend entirely therethrough without any possibility of leakage into the chamber.

While we have shown herein and described certain forms of the invention for illustrative purposes and have disclosed and discussed in detail the construction and arrangement incidental to one specific application thereof, it is to be understood that the invention is limited neither to the mere details nor to the relative arrangement of parts nor to its specific embodiment herein shown, but that extensive deviations from the illustrated form of embodiment of the invention may be made and the unloader valve claimed herein may be applied to a variety of other uses all without departing from the principles of the invention.

What we claim and desire to secure by Letters Patent is:

40 1. The combination of an air compressor cylinder and its piston with a main unloader valve therefor, an auxiliary unloader valve, and means responsive to a vacuum condition in said cylinder proper for opening said auxiliary unloader valve to relieve the work on said piston.

2. The combination of an air compressor cylinder and its piston with a main unloader valve therefor, and valve means responsive to a vacuum condition in one end of said cylinder proper for automatically relieving the work on said piston a substantial length of time after the closing of said main unloader valve.

55 3. The combination of an air compressor cylinder and its piston with unloader valve means for automatically shutting off the inlet supply of air to said cylinder, and valve means directly responsive to a vacuum condition in one end of said cylinder proper operating after the closing of said unloader valve means to relieve the compressing work of said piston.

4. The combination of an air compressor cylinder and its piston with means for auto-

matically shutting off the inlet supply of air thereto, and valve mechanisms for relieving the work on said piston on the production of a vacuum condition in said cylinder by said piston.

70 5. The combination of an air compressor cylinder and its piston, with means for automatically shutting off the inlet supply of air thereto, and simultaneously acting valve mechanisms at each end of said cylinder directly responsive to cylinder pressure for reducing the work done in said cylinder by said piston.

6. The combination of an air compressor cylinder and its piston, with an unloader 80 mechanism therefor comprising a valve, means normally closing said valve, and means responsive to a vacuum condition in said compressor cylinder for releasing said closing means.

85 7. The combination of an air compressor cylinder and its piston with an unloader valve therefor, comprising a valve, a spring pressed piston for normally closing said valve, a cylinder for the latter piston, and 90 means providing communication between said cylinders for permitting the creating by said compressor piston of a vacuum condition back of said spring pressed piston.

8. A compressor controlling valve mechanism comprising a casing containing a chamber having a wall formed to present registering valve seats, a differential valve, a spring pressed piston for normally holding said valve on its seats, and a cylinder for 100 said piston, said valve being operated in one direction by the pressure on the differential valve.

9. A compressor controlling valve mechanism comprising a casing having a wall 105 formed to present valve seats, a differential valve, a spring pressed piston for normally holding said valve on its seats, and a cylinder for said piston, said valve being operated in one direction by the pressure on the differential valve.

10. A compression controlling valve mechanism comprising a casing having a chamber therein, a differential valve for said chamber, a spring pressed piston for normally closing said valve, and a cylinder for 115 said piston, said valve being operated in one direction by the pressure on the differential valve.

11. A compressor controlling valve mechanism comprising a casing containing a chamber having a wall formed to present registering valve seats, a differential valve, a spring pressed piston for normally holding said valve on its seats, a cylinder for 120 said piston, and means for actuating said piston to release said valve.

12. A compressor controlling valve mechanism comprising a casing having a wall formed to present valve seats, a differential 130

- valve, a spring pressed piston for normally holding said valve on its seats, a cylinder for said piston, and means for unbalancing said piston to release said valve.
- 5 13. A compressor controlling valve mechanism comprising a casing having a chamber therein, a differential valve for said chamber, a spring pressed piston for normally closing said valve, a cylinder for said piston, and means for subjecting the different ends of said piston to different pressures.
- 10 14. A compression controlling valve mechanism comprising a casing, a chamber therein, valve means for controlling communication of said chamber with the atmosphere, a spring pressed piston for normally closing said valve, one side of said piston being exposed to the atmosphere, and means for creating a vacuum condition on the opposite side of said piston to release the same from said valve.
- 15 15. A compressor controlling valve mechanism comprising a casing containing a chamber, a valve for controlling communication of said chamber with the atmosphere, piston means for normally closing said valve, and means for unbalancing the pressure on said piston to release the latter from said valve.
- 20 16. A compressor controlling valve mechanism comprising a casing having a chamber therein, a valve for controlling the communication of said chamber with the atmosphere, means acting on said valve to normally close the latter, and means for unbalancing the same to release said valve.
- 25 17. A compressor controlling valve mechanism comprising a casing containing a chamber, a valve for controlling the communication of said chamber with the atmosphere, spring pressed means acting on said valve normally to close the same, and means for unbalancing the pressure on said spring pressed means to release the same from said valve.
- 30 18. The combination of an air compressor cylinder and its piston with an unloader valve mechanism therefor comprising a valve, a cylinder, a piston in said cylinder, a spring acting on said valve to hold the latter normally closed, said spring being sufficiently strong to hold said valve closed when the compressor develops a predetermined pressure, a main unloader valve for cutting off the inlet supply of air to the compressor cylinder, and means cooperating with the compressor piston and adapted to create a vacuum condition in said valve piston cylinder.
- 35 19. A compressor controlling valve mechanism comprising a casing containing a chamber, a valve for said chamber, a cylinder, and a spring pressed piston in said cylinder for normally closing said valve, said cylinder having a minute passage for permitting the leakage of atmospheric pressure therein.
- 40 20. A compressor controlling valve mechanism comprising a casing containing a chamber, a valve for said chamber, a cylinder, a spring pressed piston in said cylinder for normally closing said valve, and needle valve means for permitting the leakage of atmospheric pressure into said cylinder.
- 45 21. A compressor controlling valve mechanism comprising a cylinder containing a chamber having a wall formed to present registering valve seats, a valve having differential elements adapted to set on said seats, and a guiding stem for said valve, said valve being operated in one direction by the pressure on the differential elements.
- 50 22. The combination of a casing containing a cylinder and a chamber and having an opening communicating with the outside atmosphere, a wall in said casing formed to present a valve seat, a valve cooperating with said seat, a piston in said cylinder having a face exposed to the outside atmosphere, a spring in said cylinder for pressing said piston toward said valve to hold the latter normally seated, means for creating a vacuum in said cylinder, and a check valve for said cylinder.
- 55 23. The combination of an air compressor cylinder and its piston with unloader valve mechanisms connected with opposite ends of said cylinder, each comprising a valve, a spring pressed piston for normally closing said valve, a cylinder containing said piston, said piston being adapted upon a drop of pressure in the cylinder, to permit the valve to open, and means connecting the spring pressed piston containing cylinders of the two mechanisms for equalizing the vacuum conditions therein.
- 60 24. The combination of an air compressor cylinder and its piston with valve mechanisms for the opposite ends of said cylinder, each comprising a valve, a spring pressed piston for normally closing said valve, a cylinder for said piston, a pipe connecting the spring pressed piston containing cylinders of the two mechanisms, and a pipe connecting said pipe with said air compressor cylinder.
- 65 25. The combination of an air compressor cylinder and its piston with unloader valve mechanisms for the opposite ends of said cylinder, each comprising a valve, a spring pressed piston for normally closing said valve and a cylinder containing the same; and means providing communication between said valve mechanism cylinders and with said air compressor cylinder.
- 70 26. The combination of an air compressor cylinder and its piston with unloader valve mechanisms for the opposite ends of said cylinder, each comprising a valve, a spring pressed piston for normally closing said

- valve and a cylinder containing the same; means providing communication between said valve mechanism cylinders and with said air compressor cylinder, and check 5 valve means therefor.
27. The combination of an air compressor cylinder and its piston, with an auxiliary unloader valve mechanism therefor comprising a valve, a spring tending to close 10 said valve, a spring pressed piston for normally closing said valve, and means for releasing said piston from said valve to permit the opening thereof against the resistance of said first mentioned spring.
- 15 28. The combination of an air compressor cylinder and its piston, with an auxiliary unloader valve mechanism therefor comprising a valve, a spring tending to close said 20 valve, a spring pressed piston for normally closing said valve, and means responsive to pressure conditions in said compressor cylinder for releasing said piston from said valve to permit the opening thereof against the resistance of said first mentioned spring.
- 25 29. The combination of an air compressor cylinder and its piston with a main unloader valve and an auxiliary unloading valve mechanism comprising a valve, a light 30 spring tending to close the same, a piston, a heavy spring acting on said piston for normally holding said valve seated, and means for unbalancing the pressure on said spring pressed piston to release the same from said valve.
- 35 30. The combination of an air compressor cylinder and its piston, with a main unloader valve and an auxiliary unloading valve mechanism comprising a valve, a light 40 spring tending to close the same, a piston, a heavy spring acting on said piston for normally holding said valve seated, and means responsive to vacuum conditions in said cylinder for unbalancing the pressure on said spring pressed piston to release the same from said valve.
- 45 31. The combination of an air compressor cylinder and its piston with a main unloader valve therefor, an auxiliary unloader valve, means for normally closing the latter 50 valve, and means responsive to the pressure condition in said cylinder proper for releasing said closing means from said auxiliary valve.
- 55 32. The combination of an air compressor cylinder and its piston with a main unloader valve, a relief valve, a pressure responsive means for normally holding said relief valve closed and having provision 60 for releasing said valve on the occurrence of a predetermined drop in pressure in said cylinder.
- 65 33. The combination of an air compressor cylinder and its piston with a main unloader valve therefor for automatically shutting off the inlet supply of air to said cylinder.
- 70 34. The combination of an air compressor cylinder and an auxiliary unloader valve, means for normally holding said auxiliary valve closed, and means responsive to a drop in pressure in said cylinder proper for releasing said valve holding means.
- 75 35. The combination of an air compressor cylinder and its piston with a relief valve, pressure responsive means normally holding said valve closed, and means providing communication between said pressure responsive means and said cylinder for automatically releasing said pressure means from said valve on the occurrence of a predetermined drop in pressure in said cylinder.
- 80 36. The combination of an air compressor cylinder and its piston with a relief valve therefor, pressure responsive means for normally holding said valve closed, passage 90 means connecting said pressure responsive means and cylinder, and check valve means for said passage means.
- 85 37. The combination of an air compressor cylinder and its piston with a relief valve therefor, pressure responsive means for normally holding said valve seated, passage means connecting said pressure responsive means with said cylinder and having provision permitting the release of said pressure responsive means from said valve on the occurrence of a predetermined drop in pressure in said cylinder, and means for automatically permitting the reseating of said 100 valve by said pressure responsive means.
- 105 38. The combination of an air compressor cylinder and its piston with a relief valve therefor, pressure responsive means for normally holding said valve closed, passage 110 means connecting said pressure responsive means with said cylinder and having provision permitting the release of said pressure responsive means from said valve on the occurrence of a predetermined drop in pressure in said cylinder, and means permitting the leakage of atmospheric pressure to said pressure responsive means to render the latter effective to hold said valve in closed position.
- 115 39. The combination of a compressor cylinder and its piston, an unloader valve communicating with the cylinder and the atmosphere, means for normally holding said valve closed, controlling means for said closing means connected to said cylinder, and means for controlling said connection.
- 120 40. The combination of a compressor cylinder and its piston, an unloader valve communicating with the cylinder and the at- 125

mosphere, means for normally holding said valve closed, controlling means for said closing means connected to said cylinder, and intermittently operating valve mechanism controlled by said piston for controlling said connection.

41. The combination of a compressor cylinder and its piston, a main unloader valve, an auxiliary unloader valve communicating with the cylinder and the atmosphere, means for normally holding said auxiliary valve closed, controlling means for said closing means connected to said cylinder proper, and means operative after the closure of said main unloader valve for controlling said connection.

42. The combination of a compressor cylinder and its piston, a main unloader valve, an auxiliary unloader valve communicating with the cylinder and the atmosphere, means for normally holding said auxiliary valve closed, controlling means for said closing means connected to said cylinder, and intermittently operating valve mechanism controlled by said piston controlling said connection.

43. The combination of a compressor cylinder and its piston, a main unloader valve, an auxiliary unloader valve communicating with the cylinder and the atmosphere, means for normally holding said auxiliary valve closed, controlling means for said closing means connected to said cylinder, and means operative after the closure of said main unloader valve for closing the connection between said cylinder and said controlling mechanism during the compression stroke of the piston and opening said connection during the suction stroke thereof.

44. The combination of an air compressor cylinder and its piston with a main unloader valve therefor, an auxiliary unloader valve, and means responsive to pressure changes in said cylinder proper for opening said auxiliary unloader valve to relieve the work on said piston.

45. The combination of an air compressor cylinder and its piston with a main unloader valve therefor, an auxiliary unloader valve, and means having communication with the opposite ends of said cylinder and responsive to pressure changes in said cylinder proper for opening said auxiliary unloader valve to relieve the work on said piston.

46. In combination with an air compressor having a cylinder and piston therein, a main unloading valve, an auxiliary unloading valve, means normally closing said auxiliary valve, and a direct connection between said means and said cylinder whereby the pressure variation produced by a stroke of the compressor piston in one direction releases the unloading valve for operation by

the pressure variation produced on the return stroke.

47. In combination with an air compressor having a cylinder and a main unloading valve, an auxiliary unloading valve for each end of the cylinder, means for normally holding said auxiliary valves seated, and a direct connection between said means and said cylinder proper whereby a reduced pressure produced at one end of said cylinder may release the unloading valve at the opposite end of said cylinder.

48. In combination with an air compressor having a cylinder and a main unloading valve, an auxiliary unloading valve for each end of the cylinder, means for normally holding said auxiliary valves seated, and a direct connection between said means and said cylinder proper whereby a reduced pressure produced at one end of said cylinder may release the unloading valve at the same end of said cylinder.

49. In combination with an air compressor having a cylinder, automatic relief valve means for unloading the compressor having a connection with the atmosphere, means for normally maintaining said relief valve means closed, and means for effecting opening thereof, said means including a member having opposed surfaces one of which is exposed to the atmosphere and the other of which is connected with the cylinder, and means for permitting the flow of fluid in one direction only between said last mentioned surface and the cylinder, said relief valve means including a member controlling the said atmospheric connection and having a surface having a continuously open connection with the cylinder permitting flow to or from said surface.

50. In an unloading means for a double acting compressor cylinder, means forming a pair of passages adapted to communicate with the ends of a cylinder, a pair of valves controlling the communication of said passages with the atmosphere, means normally operating to hold said valves closed, and controlling means for said holding means connected with said passages.

51. In an unloading means for a double acting compressor cylinder, means forming a pair of passages adapted to communicate with the ends of a cylinder, a pair of valves controlling the communication of said passages with the atmosphere, and means normally operating to hold said valves closed, the holding means for one of said valves being connected with the passage controlled by the other valve.

52. In an unloading means for a double acting compressor cylinder, means forming a pair of passages adapted to communicate with the ends of a cylinder, a pair of valves controlling the communication of said pas-

sage with the atmosphere, means normally operating to hold said valves closed, and means whereby said holding means may be subjected to pressure variations in the opposite ends of a cylinder.

53. In combination with a double acting compressor cylinder having a main unloader valve adapted to close the intake of the cylinder, a supplemental unloading valve comprising passages communicating with said cylinder at points relatively longitudinally distant from each other, valves adapted when operated to permit communication between said passages and the atmosphere, means to hold said valves normally closed, and means adapted to connect said last mentioned means with the passages at the opposite ends of the cylinder therefrom whereby a reduced pressure in one end of said 20 cylinder may be transmitted to the opposite holding means.

54. In combination with a compressor cylinder, means forming a passage adapted to connect said cylinder with the atmosphere, a valve normally closing said passage, means for holding said valve closed including a surface subject to atmospheric pressure adapted to free said valve and a spring acting on an opposing surface, and means for producing a pressure less than atmospheric on said second mentioned surface and having a direct communication with an end of the cylinder.

In testimony whereof we have signed our names to this specification in the presence of two subscribing witnesses.

FRED D. HOLDSWORTH.
CHARLES W. WYMAN.
